UNITED STATES PATENT OFFICE.

AUGUST W. MEITZ, OF GRAND RAPIDS, MICHIGAN

VALVE-SEATING IMPLEMENT.

1,022,038.

Specification of Letters Patent. Patented Apr. 2, 1912.

Application filed June 19, 1911. Serial No. 634,179.

To all whom it may concern:

Be it known that I, AUGUST W. MEITZ, a citizen of the United States, residing at Grand Rapids, in the county of Kent and State of Michigan, have invented certain new and useful Improvements in Valve-Seating Implements, of which the following is a specification.

My invention relates to improvements in implements for reseating and facing check valves and globe valves, and its objects are: first, to provide an implement with which the seat and the annular ledge that surrounds the seat may be both re-formed at the same time. Second, to provide an implement with which the ledge facing cutters may be drawn together so that they will easily pass through the opening to the valve seat and can afterward be forced apart so that the projecting or cutting portion will extend over the entire width of the ledge. Third, to provide an implement which may be held positively to position so that the cutting tool or 'bur will cut the valve seat and ledge perfectly true. Fourth, to provide a means for holding the cutting portion or bur firmly to place while in operation, and, fifth, to provide a means whereby the chips may readily escape as they are cut from the valve seat, to avert the danger of clogging the cutter with said chips. I attain these objects by the mechanism illustrated in the accompanying drawing in which—

Figure 1 is an elevation of the implement with a vertical section of a valve chamber attached to show the manner of applying the implement. Fig. 2 is a sectional elevation of the standard, feed screw, the pilot nut and the valve chamber so shown to disclose the adjusting bolt, and the position of the several working elements of the implement. Fig. 3 is an elevation of the standard detached from the other elements of the implement to show its general construction and the manner of applying the facing cutters. Fig. 4 is an elevation of the implement with the valve chamber removed. Fig. 5 is a bottom plan of the reseating cutter and the pilot nut showing the passageway for chips to pass through from the cutters as the valve seat is being operated upon.

Similar letters of reference refer to like elements throughout the several views.

The standard A is made hollow far

enough down so that the adjusting bolt H may be made to adjust the facing cutters D D, as indicated in Fig. 2, and is provided with a screw thread at h' to correspond with the like thread on the surface of the adjusting bolt H. This standard has a mortise a through it for the free passage of the facing cutters D and the clamp block D', the operation of which will be hereinafter more fully explained. The lower end of the standard is solid, as at A', so that the set screw G may be properly applied to hold the clamping block D' and the facing cutters D properly in place in the mortise a, and the outer surface of this end of this standard is screw threaded, as at a', so that the pilot nut F may be screwed upon it. To set this implement ready for repairing a valve seat, the pilot nut F is screwed to place on the end of the standard A and the clamping bolt D' is inserted in the lower end of the mortise a. The reseating cutter or bur E is then placed upon the standard A above the nut F and the facing cutters D D are passed into the mortise a, as indicated in Fig. 2, when the adjusting bolt H, which has a conical point, H', tapered to correspond with the inclines d d of the cutters D D, so that when the bolt is in the position indicated in Fig. 2 the cutters D D may be made to stand in the position indicated by the solid lines in said figure, so that they will pass easily through the opening at the top of the valve chamber I, when the bolt H must be screwed downward in the standard sufficiently to force the cutters D D out over the surface of the ledge i i that surrounds the valve seat i', as indicated by the dotted lines in Fig. 2 or shown by the solid lines in Fig. 1. When the cutters D D are properly set the set screw G is screwed into the lower end of the standard until the clamp block D' presses against the lower surfaces of the cutters D D sufficiently to hold these cutters firmly, but not rigidly to place in the mortise in the standard A. When the cutters D D have been properly set and secured the collar C, which is also provided with a mortise a'' designed to pass the collar over the edges of the cutters D D, is placed upon the standard A above the cutters and the feed and guide screw B B' is placed on the standard above the collar when the whole is passed through the opening i'' at the top of the valve case I, where it is screwed down to place where the sev-

eral cutters will be brought to bear upon the valve seat i' and the ledge i . When this is done the bolt H is screwed downward until the cutters $D D$ are forced outward to the proper position, indicated in Fig. 1, and the standard A is made to revolve by applying any suitable form of wrench upon the square portion, A' , and properly turning it.

10 The cutters $D D$ are inserted a short distance into the upper surface of the cutter E as shown in Figs. 1, 2 and 3, for the purpose of insuring the forming of a perfect corner to the valve seat without danger of forming a furring that might impair the surface of the seat.

The pilot nut F must be made of a proper diameter to fit closely in the lower opening of the valve chamber so that it, together with the feed screw $B B'$, will hold the standard A to position so that the cutters must, all of them, bear properly and perfectly on the valve seat and ledge in such a manner that they cannot but cut a perfect seat and ledge, and as the cutting progresses the cutters may be kept in cutting contact with the seat and ledge by screwing the feed screw B' gradually into the valve chamber, as hereinbefore indicated. When the 20 pairs upon the valve seat have been completed the bolt H must be screwed backward or upward, which may be accomplished by applying a wrench upon the portion h and properly manipulating it, and 25 when the cutters $D D$ are liberated the feed screw B' will be screwed out of its bearing and the implement may be drawn out of the valve chamber. As the implement is drawn upward the inclines $d' d'$ on the cutters $D D$ 30 will come in contact with the shoulder i'' and the cutters will be forced toward each other until they will pass out of the opening at the top of the chamber.

The depressions shown at $e e$ in Fig. 5 40 represent openings formed the entire length of the surface of the pilot nut F to give free passage way for the chips to fall from the surface of the valve seat out of the valve chamber so that there will be no danger of 45 the chips becoming clogged with danger of greatly injuring, if not ruining the valve seat. These depressions are so located that 50 openings are formed between the pilot nut and the inner surface of the lower opening 55 of the valve chamber as indicated in Fig. 2.

The part C may be made separate from the standard A , as indicated in Fig. 2, or it may be made integral with the standard, as 60 may be readily understood by reference to Figs. 1 and 4, without any particle of difference in the operation of the implement.

What I claim as new, and desire to secure by Letters Patent of the United States, is:

1. In a valve seating implement, a hollow standard having the lower end closed and a mortise through near the said closed end, a clamping block through the lower end of said mortise, a pilot nut around the lower end of the standard a reseating cutter mounted on the standard above the pilot nut F , 70 facing cutters mounted in the mortise and bearing upon the reseating cutters and the clamping block, a set screw through the solid part of the lower end of the standard in position to act upon the clamping block 75 to hold the facing cutters to place, and a bolt passing into the hollow of the standard and adapted to adjust the facing cutters.

2. In an implement for seating valves, a hollow standard having a mortise through 80 it near the lower end and a solid portion below the mortise, a pilot nut forming a shoulder around the standard adjacent to the mortise, a reseating cutter around the standard above the pilot nut, the reseating cutter 85 grooved across the upper surface, a clamping block in the mortise in the standard, facing cutters mounted in said mortise and engaging the upper surface of the clamping block and the groove in the top of the reseating cutter, a set screw screwed through the solid part of the lower end of the standard 90 against the clamping block to hold the facing cutters to place, a collar and a feed screw mounted on the standard above the 95 reseating cutter, and a bolt mounted in the hollow of the standard for adjusting the facing cutters.

3. In an implement for seating valves, a hollow standard, having a mortise through 100 it laterally near the lower end, a pilot nut screwed onto the lower end of the standard and having depressions in the surface to form escapes for chips, a reseating cutter mounted on the standard above the pilot 105 nut, a clamping block in the mortise, facing cutters mounted in the mortise above the clamping block and the reseating cutter, a collar having mortises to pass over the facing cutters, a set screw passing up through 110 the lower end of the standard to bear upon the clamping block to hold the facing cutters to place, and a bolt within the hollow of the standard to adjust the facing cutters laterally to the width of the ledge of the 115 valve seat.

Signed at Grand Rapids Michigan June 17, 1911.

AUGUST W. MEITZ.
